 International Business Machines Corporation,
 New York, N. Y., a corporation of New York

Application June 30, 1939, Serial No. 282,204

5 Claims. (Cl. 95—4.5)

This invention relates to a recording device and more particularly to a device for preparing a color photographic film record of statistical information or data wherein the different data representations may be represented in different colors.

More specifically, the invention relates to a data photographic device for providing photographic records of data representations and in which the data representations are formed in different colors, said photographic device being under control of a statistical machine controlled by item entry means.

The photographic film records which are prepared by the device which device forms the subject matter of the present application are adapted for use in other machines for controlling the statistical and accounting operations on the said machines. In order for the film records to be effective as controlling elements in statistical machines they are provided with differentially positioned control marks or spots which by their relative positions, in the different columnar areas, on the film record denote the values of the data represented thereby. In the instant application not only are the differentially positioned spots formed in accordance with the data which they represent but in addition thereto predetermined color values are imparted to the said spots which are formed so that upon development of the film record formed by the device a record is produced which is provided with differently positioned colored data representations. The records per se just referred to are described and claimed in copending application Serial No. 282,209, filed June 30, 1939, and a suitable machine for utilizing these control records is described and claimed in copending application Serial No. 282,207, filed June 30, 1939.

In the particular embodiment of the present invention item entry means such as control keys are provided for controlling the operations of an accounting section of the device comprising adding and printing mechanism; also under control of the keys and operated by the printing mechanism are displaceable members which are differentially set in accordance with the value of the data entered in the accounting section by depression of the control keys and the positioning of the associated printing members. Manipulative means are also provided for controlling the selection of the color values of the exposed sections of the displaceable members so that upon operation of the photographic recording means the data representations are recorded upon the

film records in different predetermined colors.

Accordingly, an object of the present invention resides in the provision of means for recording statistical data in the form of differentially positioned control marks upon film records in different colors.

Another object of the present invention is the provision of means for recording photographically the statistical information created by data representing elements which indicate the values of the statistical data and for imparting different color values selectively to the data representing elements thereby determining the color of the data representations recorded on the film record.

10

Another object of this invention is the provision of means for recording photographically the differential positions of displaceable elements which by their different positions represent the values of the data to be recorded and for controlling the exposure of certain colored sections of the said elements when placed in their different positions.

15

Another object is the provision of means for recording photographically the differential positions of displaceable elements, the displacement of which is under control of the account section, which elements by their different positions represent the values of the data to be recorded and for selecting predetermined color values so that the positioned elements indicate the data represented thereby in the different selected colors.

20

Other objects of the invention will be pointed out in the following description and claims and illustrated in the accompanying drawings, which disclose, by way of example, the principle of the invention and the best mode, which has been contemplated, of applying that principle.

25

In the drawings:

40 Fig. 1 is a top plan view of the machine.

Figs. 2 and 2a taken together show a part side elevational and part sectional view of the machine, the section being taken substantially on line 2—2a of Fig. 1 looking in the direction of the arrows. Fig. 2a is substantially a side elevational view of the adding machine or entry section with the case removed and Fig. 2 is substantially a vertical sectional view of the recording section of the machine.

45

Fig. 3 is a detail sectional view taken substantially on line 3—3 of Fig. 2 and shows the driving means and clutches for the film drive and the shutter device of the camera.

50

Fig. 4 is a detail sectional view of certain parts

55

shown in Fig. 3, the section being taken substantially on line 4—4 of Fig. 3.

Fig. 5 is another detail view taken substantially on line 5—5 of Fig. 3.

Fig. 6 is a sectional plan view of a part of the photographic recording section of the machine, the view being taken substantially on line 6—6 of Fig. 2. This view shows a check in position on the bed and also shows the recording elements for recording numerical information.

Fig. 7 is a detail sectional view taken substantially on line 7—7 of Fig. 6 and shows the manner in which a numerical slide cooperates with the mask element.

Fig. 8 is a transverse sectional view of this part of the machine taken substantially on line 8—8 of Fig. 6.

Fig. 8a is a detail view of the steel strip guide groove.

Fig. 9 is a detail view of certain parts at the right hand side of the adding machine within the case, the view being taken substantially on line 9—9 of Fig. 1 and looking in the direction of the arrows.

Fig. 10 is a circuit diagram of the machine which forms one embodiment of the invention.

Fig. 11 is a fragmentary section of a portion of the film which is produced showing recorded data thereon and wherein the data representations are formed in different colors.

Fig. 12 is a detail view of the differently colored sections of the displaceable members.

Fig. 13 is a partial sectional view along line 12—12 of Fig. 2a.

Before describing the details of the structure of the machine, a brief description will be given of the operations which the machine is intended to perform. The present machine incorporates item entry means such as a keyboard entry section shown as an adding machine of known type which is arranged for printing items, taking totals, sub-totals and transfer totals, etc. Associated with the adding machine is a photographic recording device which is arranged to record on a color film the numerical data entered into the adding machine and the total data derived by the adding machine. For each entry into the adding machine and for each total printed by the adding machine on the usual adding machine tape a record is made of representations upon a color film in the form of colored areas or spots which by their relative location to each other on the film represent the numerical data entered or totaled by the adding machine. Provision is also made in the photographic recording section for recording photographically when desired, a reproduction of a check or other document. Such check or like document can be photographed on the film in juxtaposition to numerical data records derived from the adding machine. Provision is also made for photographically recording a serial number which is representative of the number of the particular photographic record. Provision is also made for photographically recording hand set up numerical data which may be representative of dates or other information. In the photographic recording section provision is also made for recording the kind of total taken by the adding machine, for example, sub-totals, grand totals, transfer totals, etc.

Referring now to Figs. 1 and 2a, the adding machine which is used to illustrate a suitable type of keyboard controlled machine is here shown as a machine of the well known Burroughs type. The adding machine proper and here il-

lustrated, is the adding and listing machine shown and described in the U. S. patent to Vincent & White, No. 919,656, dated April 27, 1909. Since according to the present embodiment a motor driven type of adding machine is provided the arrangement for motor drive of the machine is of the type shown in the U. S. patent to Vincent, No. 1,054,628, dated February 25, 1913. The adding machine will only be described briefly since reference may be made to the foregoing patents for a fuller description.

The machine comprises a set of numeral keys 100 (Fig. 1), an elimination key 101 corresponding to key 265E of the Vincent and White patent, a transfer total key 102, a subtotal key 103 and a total key 104. These latter keys correspond to keys 265T, 265S and 265 of the Vincent and White patent. There is also provided the motor bar 105, corresponding to the motor bar shown in the Vincent patent. The adding machine comprises also the usual two accumulators generally designated 106 and 107 (see Fig. 2a). The adding machine comprises also the usual type sectors controlled from the item entering keyboard and from the accumulators and which sectors are generally designated 108 in Fig. 2a. Such sectors correspond to part 618' of the Vincent and White patent.

Referring now to Fig. 9 this figure shows a portion of the linkage intermediate the motor bar 105 and the motor driven clutch. This mechanism is generally similar to the mechanism shown in Fig. 1 of the Vincent patent. Shaft 109 (Fig. 9) corresponds to shaft 200C of the Vincent and White patent and this shaft is adapted to be rocked to differential extents on different total taking operations. Shaft 110 of Fig. 9 corresponds to the shaft 6 of the Vincent patent and such shaft 110 in the present machine is utilized not only for driving the adding and listing machine but for also driving the photographic recording mechanism. For this purpose the shaft 110 at its opposite end (see Fig. 2a) is provided with a gear 111 which drives a gear 112 fixed to a shaft 113 which extends to the photographic recording station of the machine.

The connections from the adding and listing machine section to the photographic recording section comprise three trains of mechanism. One train of mechanisms extends from the various type sectors 108, another train comprises the shaft 113 just referred to and another train comprises a link connection to the shaft 109 previously referred to. The train to the sectors 108 will be first described.

Referring to Figs. 1, 2 and 2a, each of the type sectors 108 has connected to it an upstanding arm or link 114, each of which at its upper end connects to a lever 115. Each of these levers 115 at its rear end (see Fig. 2) connects to a downwardly depending link 116 which in turn, through a bell crank member 117 is adapted to displace a horizontally disposed link 118. To aid in the displacement of these parts 114, 115, 116, 117 and 118, springs 119 are provided.

Each link 118 has connected to it a displaceable or slideable member 120 (Fig. 7) each of which in turn supports a tubular member 122 (see Fig. 12) which is divided into differently colored sections. In Fig. 12 four differently colored sections are indicated by the reference characters 122a, 122b, 122c and 122d. Members 120 and 122 are slidably mounted on shaft 50 and the member 122 is arranged so as to be rotated by means of the said shaft. The degree of rotation

of shaft 50 and consequently the member 122 determines the color of the data representation or spot which will appear on the mask 121 and on the colored photographic film record. The means for controlling the selection of the colored sections of the displaceable members will be described later herein. The individual members 122 are arranged to be slidably displaced beneath the mask 121 having the differently positioned perforations 122f formed therein. The top surface of the mask is preferably white in color. In order to provide a complete white background during the photographic process, all the perforations 122a in the mask except the selected ones in each columnar position should be white to match the color of the mask. For this purpose, individual steel strips 120a are provided and secured to each of the slidable members 120 so that the said strips, the top surface of which is white, are slidably displaced beneath the mask. A perforation or aperture 120b is provided in each of the strips so that the colored section of the tubular member 122 can be exposed and viewed from the top of the mask. The slidably arranged strips 120a are guided by means of grooved slots formed by the elements 120c as shown in Fig. 8 and particularly in Fig. 8a wherein the strip 120a and member 120 are removed. Now, it is understood that upon positioning of the parts 117, 118, 120, 122 and 120a that all the non-selected apertures in the mask are provided with a white background by means of the positionable strips 120a. By referring to Fig. 6 it will be noted that by differentially displacing the tubular members 122 the differently colored spots 122b will present an appearance through the mask 121, the same as they would if these colored spots were painted on the top of the mask at the different index point locations. In this manner any setting of the type sectors 108 of the adding machine will set up a corresponding arrangement of spots through the perforated mask and set up representations of numerical data. The apertures of the mask preferably have a spacing corresponding to the index point positions of a tabulating card, see the patent to Lake No. 1,772,492. It will be understood that there is a member 122 for each type sector 108. A supplemental slide and tubular member 120T is also provided for indicating total and transfer total data. The supplemental slide is disposed beneath the extreme right hand columns of openings through the mask and such supplemental slide 120T is operated by a horizontal link 118T (see Fig. 2) which cooperates with a lever 117T connected to a link 116T (Fig. 2a). 116T at its forward end connects to a lever 123 which is fixed to a rock shaft 124 (see Fig. 9), extending across under the adding machine and having fixed to its opposite end a lever 125 to which a vertical extending link 126 is connected. The link 126 at its upper end connects to an arm 127 which is fixed to the shaft 109. The shaft 109 is differentially rocked in total taking operations and the train of linkage just described is adapted to differentially shift the total recording slide 120T in the photographic recording section for setting up representations of total designating data to be photographed. For the purpose of restoring the total linkage just described a supplemental restoring spring 128 can be provided (see Fig. 9).

Referring again to Fig. 6, the mask 121 is provided with an angle plate 129 disposed adjacent the numerical data zone of the mask. In the

use of the machine a document such as a check 130 can be placed by hand in position abutting this angle plate and the data from this check can be photographically recorded. This photographic recording section is provided with a check receiving opening in the front of the housing and to the left of the left side of the adding machine (see Fig. 1) so that the check can be placed in position by hand.

Referring again to Figs. 2 and 6, there is an opening 131 provided through the mask through which the numeral wheels 132 of a Veeder type counter can be viewed and photographed. This Veeder type counter is of the customary step by step variety and is preferably electromagnetically actuated by a rocking armature member 133 which is adapted to be rocked by the energization of an actuating electromagnet 134. In Fig. 2 reference character 135 shows the housing for the wheels of the counter.

If desired (see Fig. 6) other data such as the name of a bank, etc., may be printed on the top of the mask in any desired location, here shown in proximity to the counter opening 132, such data being indicated at 136. In certain cases it may be desirable to set up by hand representations of supplemental numerical data. For this purpose the mask 121 is provided with a supplemental zone beneath which there are disposed a number of hand set slides 120S. These slides are similar in construction to the slides 120 previously referred to and they may be moved by hand through members 118S to set up representations of fixed data which are to be photographically reproduced with the variable numerical data.

The mask is preferably provided with a black line 137 for providing a reference line indicating mark on the film upon photographing. Such reference line is shown in the film (Fig. 11) as 137a.

The selecting means for determining the color values to be imparted to the data representations will now be described. Referring now to Figs. 1, 2, 2a and 13 a plurality of settable levers 66a to 66d are shown, one for each of the color values desired to be recorded. In the instant illustration the data representations can be recorded in four different colors, green, blue, red and black, for this reason four individual selecting levers 66 are provided, each lever also being provided with four camming surfaces 68a to 68d. Each of the said levers can be manually positioned in one of four positions for selecting the colored section of the tubular member 122 it is desired to expose to the photographic device. In order to describe briefly the principle of the selection operations assume the lever 66d to be set for recording the data in the color red. Cooperating with the extension 74 of the links 64a to 64d is a common bail 65 which is supported by an extension of the member 300 loosely mounted on shaft 301. Member 300 corresponds to the member 613 in the Vincent patent referred hereinabove and the shaft 301 is identified in this patent by the reference character 600. Said member 300 is lowered each computing cycle so that the type sections 108 can be raised and stopped at the differential positions in accordance with the operation of the control keys. Now, whenever the member 300 is lowered the bail 65 is raised so that the links 64a to 64d can be urged in an upward direction by means of the springs 69. The extent of the upward movement during each computing cycle is determined by the camming

surfaces provided on the levers 66a to 66d. Since the lever 66d is positioned to select the red sections of the tubular members 122, the camming surface 68c is effective to prevent further upward movement of the link 64d. These links 64a to 64d at the end of the computing cycle are again restored to the normal condition indicated in the drawings by the said bail 65. The individual rack 58d upon movement of link 64d is positioned a predetermined distance by means of links 60 and 61, the latter being secured to the individual tubular shaft 62d which is rotatably mounted on shaft 63, link 73 which is also secured to the said tubular shaft and connected to the individual and corresponding link 64d. Thus it is seen that the said rack is displaced a predetermined distance depending upon the upward movement of link 64d. The remaining racks 58a to 58c are positioned similarly as rack 58d by similar connecting links between the corresponding racks 58a to 58c and links 64a to 64c. Provision is made whereby the movements of the said racks can be transmitted to the individual shafts 50 by means of elongated gears 51 fastened to the said shafts and individual idler gears 52. It is understood that an individual gear 52 is provided for each tubular member 122 and its associated shaft 50 and gear 51. The purpose of this arrangement is to permit each tubular member 122 to be set to expose any desired colored section to the photographic zone. The amount of rotation imparted to shaft 50 determines which colored section is positioned beneath the apertures 122f in the mask. The amount of rotation of shaft 50 is determined by the displacement or movement of the racks 58a to 58d.

Now to continue with the example, assume that all the idler gears 52 are positioned so as to engage the rack 58d thereby transmitting the movement of the said rack to the individual shafts 50 so as to position the red sections of the tubular members 122 beneath the apertures 122f in the mask. Positioning of the said idler gears 52 is effected by means of the selecting levers 70a which can be positioned to one of four positions, each position corresponding to an individual rack, and the connecting link 70 and crank lever 55 pivotally mounted on shaft 59. Each crank lever 55 cooperates with a corresponding tubular shaft 53 to which a gear 52 is secured. The said gear and shaft assembly are slidably mounted on rod 54. Individual selecting levers 70a are provided for each tubular member 122. Thus it is seen that the controlling shaft 50 and associated gear 51 can be connected by means of the positionable idler gear 52 to any one of the racks 58a to 58d.

Photographic recording device

Referring further to Figs. 2a and 9, the shaft 110 makes one complete rotation upon each depression of the motor bar 105 and upon each motor driven actuation of the adding machine. This rotation of shaft 110 is utilized for effecting and controlling the operations of the camera element including film feeding and exposing.

Referring to Fig. 2 the shaft 113 at its end, through gearing 138, drives a vertical shaft 139, which vertical shaft in turn through gearing 140 (see also Fig. 1) drives (see Fig. 3) the notched element 141 of an electromagnetic one revolution clutch (see also Fig. 4) which is revolvably mounted on a clutch shaft 142. The complementary part of this one revolution clutch com-

prises a pawl carrier arm 143 fixedly carried on the clutch shaft 142. 143 has pivotally secured to it the usual pawl or dog 145 which is adapted to be released to engage with the notch of the element 141 upon the rocking of the armature 146 upon the energization of the clutch magnet 147.

Film feed

The clutch shaft 142 has fixed to it a mutilated gear 148 (Fig. 5) and a locking element 149 of a Geneva device. The mutilated gear coacts with the gear 150 and the locking element 149 cooperates with the other part of the Geneva designated 151. Gear 150 through an idler 152 drives a gear 153. Gears 150 and 153 are respectively fixed to sprocket shafts 154 and 155. Upon engagement of the electromagnetic one revolution clutch the sprocket shafts 154 and 155 will be turned one-quarter of a revolution to advance the color film in the camera 156, (see Fig. 2). The sprocket shafts have the usual film feeding sprockets 157 and 158 driven thereby. The color film is advanced by the drive just mentioned from a supply roll 159 to a take-up roll 160. The take-up roll is preferably driven by a slipping belt drive connection 161.

Shutter actuation

In Fig. 2 the part generally designated 162 is the shutter of the camera which may be of any desired type. The usual lens is in association with the shutter. The shutter operating shaft is designated 163. Referring now to Fig. 5 provision is made for rocking the shutter operating shaft 163 after the color film has been fed. For rocking this shutter shaft a cam member 164 is provided fixed to the gear 148 (see also Fig. 3) and such cam 164 is adapted to rock a spring restored lever 165 and therethrough rock the shutter shaft 163 and exposure of the color film.

The camera 156 as shown in Fig. 2 is mounted a distance up above the mask and for illuminating the mask, lights 166 may be provided.

The operation of the machine will now be generally described.

It will be understood that data may be photographically recorded from an inserted document or the recording of data from the document may be dispensed with. Under the assumption that check data is to be entered on the adding machine and the check recorded, the operation would be as follows. The operator of the machine first sets up on the amount keys on the adding machine or keyboard section the desired data from the check. After the data has been read from the check and entered on the adding machine keyboard, the operator places the check in position in the photograph recording section against the abutment 192. Thereafter the operator depresses the motor bar 105 of the adding machine. The operating cycles of the adding machine ensue and during the early part of the rotation of the shaft 110, a section of the color film is fed forward in position for receiving an image. While the said film is being fed forward the sectors 108 of the adding machine move toward the printing line. Such movement of any sector from its normal no print position to beyond the zero position displaces a bail 167 (Fig. 2a) upwardly to cause a contact spring 168 to ride off an insulated block 169 and establish contact with a conducting segment strip 170. The relation of parts is such that contact between 168 and 170 is not established unless

some particular sector of the group of sectors has moved to bring a significant figure to the printing line. This control is provided for suppressing film feed and photographic recording operations when the adding machine is making an idle stroke. The movement of the sectors 108 to printing position differentially displaces the members 122 to set up a proper representation of the data which is to be photographically recorded under control of the adding machine or keyboard entry device through the mask.

Concurrently with the positioning of the type sectors, links 64a to 64d are urged in an upward direction to be set or positioned in accordance with the setting of the levers 66a to 66d. Due to the positioning of the said links the corresponding racks 58a to 58d are displaced predetermined distances which movements are imparted to the tubular members 122 by means of the positioned idler gears 52 thereby effecting not only differential positioning of the tubular members 122 to indicate the data entered into the accounting section of the device, but also effecting a rotational displacement of the tubular members so that predetermined colored areas are presented to the photographic zone so that the data representations are photographed in color in accordance with a predetermined selection.

Referring to Fig. 2a, a commutator 171 is also provided on shaft 110 having a single conducting spot 172 adapted to cooperate with brushes 173 upon the rotation of the commutator.

Referring now to Fig. 10, the camera clutch magnet 147 and the serial number magnet 134 are disposed in a circuit which extends to the wiping contact element 168. The segment 170 is connected in a circuit to one of the brushes 173 and the other brush 173 is connected back to the other side of the line. The segment strip 172 on the commutator 171 is in such relation on the commutator that it will complete a circuit through the camera clutch magnet 147 and the serial number magnet 134 just after any type sector has moved past the zero position and effected the completion of the circuit between 168 and 170. Accordingly, during the movement of the type sectors 108 to printing position for printing a significant number entered into the adding machine from the keyboard, film feed will be initiated. At the time the type hammers of the adding machine take their imprint from the type sectors the shutter device is timed to be operated and to cause an exposure to be taken of the colored representations appearing on the mask and of the inserted check or other document.

On total taking operations there is an idle operating cycle of the adding machine before total taking. On such idle stroke, film feed and exposure of the film will not occur since under this idle operation 168 will not establish contact with 170. However, on the subsequent actual total printing operations the contact will be established and there will then be recorded on the film a representation of the total together with the character of the total, the representation of the character of the total being obtained through the supplemental slide 120T.

Referring to Fig. 11 this shows a fragmentary section of a color film produced by the photographic recording section. On this section of film, 200 are the feed sprocket apertures in the film. The data represented at 201 represents a reproduction of a document. The data representations in zone 202 represent amounts set up 75 for controlling the first mentioned means to ef-

from the hand setup devices. The data at zone 203 represents numerical data entered from the keyboard of the machine. In the lower photographic record the data at 204 represents the class of total operation and the data at 205 represents numerical result data derived from the accumulating section of the accounting machine.

The serial number reproduction is indicated at 206 and the supplementary data from the mask is indicated at 207. It will be understood that the completed film has photographic reproductions thereon at successively spaced intervals along the film and that the reproductions are in extremely compact form. The films used may be negative films or films which during development are reversed to positives. The film delineated is a positive. It is understood, that the data representations will be formed on the film in different colors in accordance with the selections made during the operation of the machine.

The mechanism described hereinabove without provision for recording the data in different color values is described and claimed in copending application Serial No. 646,827, filed December 12, 1932, which now has matured into U. S. Patent No. 2,211,847.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A photographic recording device for recording indicated data images in color upon a light sensitive medium capable of registering the said images in color comprising an objective, means to control the exposure of the said light sensitive medium through the objective to the indicated data, a plurality of positionable data indicating elements, data selecting means for controlling the positioning of the indicating elements in accordance with the selected data, rotatable color indicating means, one for each indicating element, and carried by the latter, selectively operable means for controlling the positioning of the said rotatable color indicating means whereby the latter indicate the selected data in the desired colors, and means controlled by said data selecting means for controlling the first mentioned means to effect exposure of the said light sensitive medium to the selected data images having the selected color values thereby causing the said images to be recorded, in color on the said medium.

2. A photographic recording device for recording indicated data images in color upon a light sensitive medium capable of registering the said images in color comprising an objective means to control the exposure of the said light sensitive medium through the objective to the indicated data, a plurality of positionable data indicating elements, data selecting means for controlling the positioning of the indicating elements in accordance with the selected data, color indicating means carried by said indicating elements, selectively operable means for controlling the said color indicating means whereby the latter indicate the selected data in the desired colors, and means controlled by said data selecting means for controlling the first mentioned means to ef-

fect exposure of the said light sensitive medium to the selected data images having the selected color values thereby causing the said images to be recorded in color on the said medium.

3. A photographic recording device for recording indicated data images in color upon a light sensitive medium capable of registering the said images in color comprising an objective, means to control the exposure of the said light sensitive medium through the objective to the indicated data, a plurality of positionable data indicating elements, data selecting means for controlling the positioning of the indicating elements in accordance with the selected data, means cooperating with the data indicating elements for indicating the selected data in the desired colors having selectively operable means for controlling the color indicating means, and means controlled by said data selecting means for controlling the first mentioned means to effect exposure of the said light sensitive medium to the selected data images having the selected color values thereby causing the said images to be recorded in color on the said medium.

4. A photographic recording device for recording indicated data images in color upon a light sensitive medium capable of registering the said images in color comprising an objective, means to control the exposure of the said light sensitive medium through an objective to the indicated data, a plurality of data indicating elements, data selecting means for controlling the conditioning of the indicating elements in accordance

with the selected data, said indicating elements having means for indicating the data in different colors, manipulative means for determining the colors in which the data images are to be recorded, means controlled by the manipulative means for controlling the said color indicating means to impart predetermined color values to the selected data indicating elements, and means for controlling the first mentioned means to effect exposure of the said light sensitive medium to the selected data images having the selected color values thereby causing the said images to be recorded in color on the said medium.

5. A photographic recording device for recording indicated data images upon a light sensitive medium capable of registering the said images in color comprising an objective, means to control the exposure of the said light sensitive medium through the objective to the indicated data, a plurality of data indicating elements, data selecting means for controlling the conditioning of the indicating elements in accordance with the selected data, selectively operable means cooperating with the data indicating elements having means for imparting predetermined color values to the selected indicating elements, and means for controlling the first mentioned means to effect exposure of the said light sensitive medium to the selected data images having the selected color values thereby causing the said images to be recorded in color on the said medium.
